UNITED STATES PATENT OFFICE.

MILAN C. BULLOCK, OF CHICAGO, ILLINOIS.

VALVE FOR STEAM-ENGINES.

SPECIFICATION forming part of Letters Patent No. 407,994, dated July 30, 1889.

Application filed September 6, 1887. Serial No. 248,942. (No model.)

To all whom it may concern:

Be it known that I, MILAN C. BULLOCK, of Chicago, in the county of Cook and State of Illinois, have invented certain new and useful 5 Improvements in Valves for Steam-Engines; and I do hereby declare that the following is a full, clear, and exact description thereof, reference being had to the accompanying drawings, and to the letters of reference marked 10 thereon, which form a part of this specification.

My invention has for one of its objects to provide for a partial steam-balance of a slide-valve and for another to lessen the distance between the valve seat or bottom of the steam-chest and the bore of the cylinder, whereby 15 the steam-passages leading from the steam-chest to the piston-chamber or cylinder-bore are reduced to their minimum length.

To these and other ends, which will hereinafter further appear, my invention consists 20 in the matters set forth in the following description and pointed out in the appended claims.

In the drawings, Figure 1 is a plan of the 25 valve-seat, showing the several ports in the same, the steam-chest being removed. Fig. 2 is a top view of the slide-valve of my improved construction. Fig. 3 is a view of the sliding face of the valve, showing its several ports 30 and the central chamber by which the partial balancing of the valve by steam-pressure is attained. Fig. 4 is a central transverse section of the engine-cylinder, the steam-chest, and the valve; and Fig. 5 is a central longitudinal section of the cylinder, steam-chest, 35 and valve.

A represents the cylinder of a steam-engine, B the steam-chest, and C a slide-valve. The valve-seat A' on the cylinder-casting is 40 provided with transverse steam-ports A² in the usual positions and a longitudinally-arranged exhaust-port A³, placed at one side of the steam-chest or valve-seat, as seen in Figs. 1 and 4.

45 The slide-valve C is provided with exhaust-ports C' C', in proper position to work in connection with the ports A² in the valve-seat, which ports C' communicate with an interior chamber C² in the valve, having a discharge 50 opening or port C³, arranged longitudinally of the valve or at right angles with the ports

C' and at one side of the valve in position to coincide with the port A³ in the valve-seat. The valve C has a passage through it (here shown in the form of a notch or recess C⁴) at 55 the side thereof opposite the port C³, as seen in Figs. 2, 3, and 4, and this passage is extended in the under face of the valve, forming a shallow chamber C⁵. (Seen in Figs. 3, 4, and 5.) By means of this chamber C⁵, communicating through the passage C⁴ with the general interior of the steam-chest B, steam is admitted beneath the valve to the extent of the horizontal area of this chamber, and to a corresponding extent the steam so admitted 60 below the valve counterbalances the pressure of the steam upon the top of the valve, while the top pressure is also lessened to the extent of the passage C⁴. The chamber C⁵ is located about centrally of the valve, in order that the 65 relief afforded thereby shall be distributed in its effects of wear and friction about equally over the entire valve-face. Said chamber C⁵ may in practice be made somewhat deeper in proportion than shown in Figs. 4 70 and 5 of the drawings. As here illustrated, and as an additional improvement, a transverse recess A⁴ is provided in the cylinder-casting centrally between the ports A² and 75 extending beyond the chamber C⁵ into free communication with the passage C⁴, whereby steam is more freely admitted beneath the valve. The relation of the recess A⁴ to the notch C⁴ in the seat of the valve is shown 80 clearly by dotted lines in Fig. 2, from which 85 it will be seen that steam has ready access to the chamber C⁵ by said recess A⁴.

A tube C⁶ extends through the chamber C² of the valve C, fitted steam-tight at its ends in the end walls of the valve. This tube gives 90 passage to the valve-stem D, upon which the valve is adjustably secured by the nuts d d, applied to the stem D, one at each end of the valve. The tube C⁶ is made of larger interior diameter than the stem C, for the purpose of allowing a vertical movement of the valve without a corresponding movement of the stem, as may be required by the wear of the valve face and seat or by the presence of water in the cylinder in starting the engine, 95 which may cause the valve to rise clear of its seat to give escape to the water.

On the top of the valve is provided an oblong plane surface c , Figs. 2, 4, and 5, finished parallel with the valve-face. Upon this surface bears a button E, laterally confined in a 5 socket F in the under surface of the top plate of the valve-chest B, and between said button E and the said top plate of the chest B is placed a spring G, Figs. 4 and 5, which exerts its force to press the valve against its 10 seat.

In the construction of the valve as shown the ports of the cylinder may be direct, or as 15 nearly direct as desired, in their course through the cylinder-wall, and the central chamber heretofore provided in the cylinder-casting for the exhaust over the highest line of the cylinder-bore is dispensed with. As a 20 result the cylinder-passages are shortened both by their more direct course and by the thinner body of metal required between the cylinder-bore and the valve-seat, the advantage of which is manifest to those acquainted with the art.

I claim as my invention—

1. The combination, with a steam-engine cylinder provided with a flat valve-seat having transversely-arranged ports A^2 A^2 near the ends of the cylinder and a longitudinally-arranged exhaust-port A^3 , located at one side 30 of the valve-seat and communicating with an exhaust-passage cast in the metal of the cylinder, of a chambered slide-valve having a flat bearing-face in contact with the valve-seat, and provided in said bearing-face with 35 ports C' C' and C^3 , operating in connection with the ports A^2 A^2 A^3 , substantially as described.

2. The combination, with a steam-engine cylinder provided with a flat valve-seat having transversely-arranged ports A^2 A^2 near

the ends of the cylinder and a longitudinally-arranged exhaust-port A^3 , located at one side of the valve-seat, of a chambered slide-valve having a flat bearing-face in contact with the valve-seat, provided in said bearing-face with 45 transverse ports C' C' near its ends and an intermediate longitudinally-arranged port C^3 at one side, and having a central recess or chamber C^5 , located in the flat face of the valve between said ports and in communication with 50 the steam-space of the valve-chest at the side of the valve opposite the said port C^3 .

3. The combination, with a steam-engine cylinder provided with a flat valve-seat having transversely-arranged ports A^2 A^2 near 55 the ends of the cylinder and a longitudinally-arranged exhaust-port A^3 , located at one side of the valve-seat, of a chambered slide-valve having a flat bearing-face in contact with the valve-seat, and provided in said bearing-face 60 with transverse ports C' C' and with a longitudinally-arranged port C^3 , located at one side of the valve-seat, said valve being also provided with a recess C^4 , extending through the 65 valve from top to bottom surface thereof in the side of the same opposite said port C^3 , substantially as described.

4. The combination, with a valve-seat provided with steam-ports A^2 , a side exhaust-port A^3 , and a central transverse recess A^4 , of a 70 slide-valve having a chamber C^5 , and a passage C^4 , communicating with said chamber and with the recess A^4 , substantially as described.

In testimony that I claim the foregoing as my invention I affix my signature in presence 75 of two witnesses.

MILAN C. BULLOCK.
